[57] CLAIM

The ornamental design for a contoured fabric doll head, substantially as shown and described.

DESCRIPTION

FIG. 1 is a front elevational view of a contoured fabric doll head showing my new design;

FIG. 2 is a left side elevational view thereto, the right side elevational view being identical thereof;

FIG. 3 is a top plan view thereof;

FIG. 4 is a back elevational view thereof;

FIG. 5 is a bottom plan view thereof;

FIG. 6 is a sectional view taken substantially along the line 6—6 of FIG. 1.
